MACHINE TOOL

Ezekiel Field White, West Hartford, Conn.

Application April 25, 1942, Serial No. 440,463

30 Claims. (Cl. 82—2)

My invention relates to machine tools.

It has among its objects to provide an improved so-called "automatic" and, more particularly, such a machine tool which, while not limited thereto, is especially adapted to use in turning projectiles such, for example, as armor piercing bullets for rifles, machine guns, etc., or projectiles of larger caliber. A further object of my invention is to provide such an improved machine tool having improved driving connections between the spindle and the cam shaft whereby it is made possible to eliminate the gearing heretofore used in such tools and produce an exceedingly simple mechanism. A further object of my invention is to provide such an improved machine tool having such improved driving mechanism between the spindle and cam shaft including cooperating eccentric mechanism on the spindle and cooperating overrunning clutch mechanism on the cam shaft and rotatable by said eccentric mechanism, whereby the above advantages are obtained at the same time that, through possible adjustments of the eccentric mechanism, a wide variation in cam shaft speed relative to spindle speed is made possible. A still further object of my invention is to provide such cooperating mechanisms having improved associated mechanism controlled by the cam shaft for controlling the gripping and feeding mechanism associated with the spindle. Another object is to provide improved cutting tool operating and controlling mechanism likewise controlled and operated by the cam shaft for adjusting the cutting tools toward and from the work being rotated by the spindle, and wherein, while also intermittently feeding the tools, improved provision is made for holding each tool against the work upon completion of the tool feeding movement, i. e. without advancing the tool upon the work, in order to produce accurately round work. Other objects of my invention are to provide improved cooperating controlling mechanism for effecting speeding up of the rotation of the cam shaft relative to the driving spindle during a part of the cycle of operation of the machine in such manner as markedly to increase production, improved cutting tool carrying and actuating mechanism controlled and operated by the cam shaft for effecting an improved control and operation of a pair of cooperating roughing and finishing tools, improved adjustable eccentric mechanism for varying the cam shaft speed relative to the spindle speed, and improved manually adjustable operating and controlling mechanisms for effecting at will manual rotation of the cam shaft independently of its normal drive from the

spindle and while the spindle continues to rotate the work, and an improved selective manual control of the cam shaft drive. These and other objects and advantages of my improvements will, however, hereinafter more fully appear.

In the accompanying drawings, I have shown for purposes of illustration certain embodiments which my invention may assume in practice.

In these drawings:

Fig. 1 is a side elevation of my improved machine in use in making bullets; associated conveyor mechanism being shown in operative position beneath the tools;

Fig. 2 is a front elevation of the machine with the stock stop structure and the conveyor mechanism removed to facilitate illustration, and also showing the tools in non-cutting position;

Fig. 3 is an enlarged detail view of the tools and their operating cams shown in Figure 2 but with the tools in different positions and the finishing tool approaching cutting off position;

Fig. 4 is a detail section on line 4—4 of Fig. 3;

Fig. 5 is a similar view but showing the tools in the position occupied when the roughing tool is operating;

Fig. 6 is a view similar to Fig. 4 but showing a modified form of tools;

Fig. 7 is a rear elevation of the machine shown in Figure 2;

Fig. 8 is a detail view showing the speeding up mechanism for the cam shaft when the spring thereof is compressed and just as the latter is about to effect a speeding up operation;

Fig. 9 is a similar view showing this mechanism in its position at substantially the end of the speeding up operation;

Fig. 10 is a developed view of the tool feeding cams controlled by the speeding up mechanism;

Fig. 11 is a longitudinal enlarged sectional view on line 11—11 of Fig. 2;

Fig. 12 is an enlarged transverse sectional view on line 12—12 of Fig. 1;

Fig. 12a is a detail sectional view on line 12a—12a of Fig. 12;

Fig. 13 is a detail section on line 13—13 of Fig. 1;

Fig. 14 is an enlarged lay-out of the cam operating the roughing tool;

Fig. 15 is a like lay-out of the cam operating the finishing and cutting off tool;

Fig. 16 is a detail view of a modified form of adjustable eccentric mechanism on the hub of the driving pulley on the spindle shaft;

Fig. 17 is an end elevation of Fig. 16, with the spindle mechanism in section;

Fig. 18 is a detail section on line 18—18 of Figure 17;

Fig. 19 is a sectional view of a modified form of the overrunning clutch shown in Fig. 12;

Fig. 20 is a front diagrammatic elevation of a series of machines and their associated supports and conveyor mechanism;

Fig. 21 is a rear elevation showing a modified form of speed up mechanism for the cam shaft drive;

Fig. 22 is a sectional view on line 22—22 of Figure 21, and

Fig. 23 is an enlarged detail of the modified cam mechanism.

In the illustrative construction shown in Figures 1 to 15, I have shown the machine as including a main skeleton frame 1 mounted on a suitable support 2 and carrying on the top of the frame 1 a motor 3 driving through a belt 4 a pulley 5 fixed to a spindle 6; improved driving mechanism being provided between the longitudinally disposed spindle 6 and a longitudinally disposed upper cam shaft 7, both suitably journaled in spaced uprights 1a on the frame 1 and cooperating as hereinafter described with associated stock gripping and feeding mechanisms and cutting tool operating mechanism, in such manner that the rotating stock 8 is intermittently fed through the spindle 6 to cooperating roughing and finishing tools 9 and 10, to form and cut off successive finished pieces or bullets 11, all as hereinafter more fully described.

Referring to the improved driving mechanism between the spindle 6 and the cam shaft 7, it will be noted that I have herein provided a plurality of such driving connections on opposite sides of the pulley 5. Herein, each of these driving mechanisms includes an adjustable eccentric mechanism, generally indicated at 12, and including an outer eccentric ring 13 and having these outer rings on the two mechanisms 12 so disposed at 180° relative to one another as, during each revolution of the spindle 6, to impart successive outward swinging movements to pivoted clutch follower arms 14 which, in turn, operate overrunning clutches 15 carried thereby and operating on the cam shaft 7. Thus, for each revolution of the spindle 6, the cam shaft 7 is given two rotative impulses, herein in the counter-clockwise direction indicated in Fig. 12, in such manner as thereby to effect rotation of the cam shaft 7 at the desired reduced speed relative to the spindle 6, determined by the adjustment of the eccentric mechanisms 12.

Referring more particularly to the eccentric mechanisms 12 indicated in full and dotted lines in Figure 12, note that each such mechanism includes, in addition to the outer eccentric ring 13, an inner eccentric ring 16, herein suitably adjustably attached to the spindle 6 as by set screws 17, and having its outer eccentric surface 18 engaging the inner eccentric surface 19 of the ring 13. Herein, the member 16 has its eccentric surface 18 disposed at the base of a shoulder 20 thereon, and further has a reduced threaded portion 21 on which a holding ring 22 is threaded in such relation as to clamp the ring 13 between the shoulder 20 and the adjacent face of the holding ring 22. As a result of this construction, including the two eccentric members 13 and 16, it will be apparent that by changing the angular relation of the rings 13 and 16, the eccentricity of the ring 13, and consequently the throw ex-

erted by the latter on the follower 14, may be varied within wide limits, in such manner as thereby to vary the length of the impulses imparted to the cam shaft 7 by the overrunning clutches 15. Further, it will be apparent that, regardless of the position of adjustment of these eccentric rings 13 and 16, with the relation of the two eccentric mechanisms to one another so maintained that the outer eccentric rings 13 of the different eccentric mechanisms will throw out the different follower arms 14 at points 180° apart, a substantially continuous rotation is imparted to the overrunning clutches 15 in such manner as thereby to provide, due to inertia effects, a continuous rotation of the cam shaft 7.

Referring to the overrunning clutch mechanisms 15, each of the same herein includes an outer driving clutch member 23, fixed to the upper end of a follower arm 14, and also an inner driven clutch member 24 keyed to the shaft 7 at 24a and having portions 25 on which the outer clutch member is journaled, and also having angularly disposed slots 26 having rollers 27 therein normally biased toward the small end of the slots 26 by suitable spring mechanisms 28. Herein, three such slot and spring pressed rollers are provided equally spaced around the driven member 24 between the journaled portions 25. Also, each follower arm 14 comprises a pair of rigidly connected spaced follower plates 29, suitably connected to the driving clutch member 23 as by bolts or rivets 30, and extending downwardly and angularly with respect to the member 23 in the relation shown in Figure 12. As shown, a spring 31 also biases the follower arm 14 into engagement with the outer surface of its eccentric ring 13 and is suitably connected at its opposite ends to a suitable pin 32 on the frame and to a pin 32a carried by the spaced plates 29. At its lower end, each follower arm 14 also carries a suitable cam follower 33, preferably of frictionless type, as, for example, a ball bearing carried on a pin 34, generally similar to the pin 32a. As a result of this construction, as each eccentric ring 13 throws out its cam follower 33, the follower arm 14 is swung to the right in Figure 12 in such manner as thereby to move the outer driving clutch member 23 counter-clockwise and thereby cause the rollers 27 to be moved toward the smaller end of the slots 26 and, accordingly, through their wedging action connect the driving clutch member 23 to the driven clutch member 24 to effect rotation of the shaft 7.

Upon the continuously rotating cam shaft 7, improved operating cam mechanism, herein including cams 35 and 36 spaced longitudinally on the shaft 7, is provided for operating both the feeding and gripping mechanisms associated with the spindle 6, as hereinafter described, as well as improved roughing and finishing cams 37 and 38 for operating the tools 9 and 10, also longitudinally spaced on cam shaft 7. Herein, these two sets of cams are provided on opposite extremities of the cam shaft 7 outside the upstanding portions 1a of the frame 1 and in which portions the shaft 7 is also journaled.

Referring first to the cams 35 and 36, which operate the feeding and gripping mechanisms, note that herein the cam 35 operates the feeding mechanism and that cam 36 operates the gripping mechanism. Both as shown herein are integrally united and connected by a common sleeve 39 suitably fixed to the shaft 7, while each of these cams is also in the form of a grooved cam. As shown, cam 35 cooperates with

a suitable follower 44 carried on a lever 45 pivoted at 46 above a rearward extension 47 on the frame 1 in which the rear end of the cam shaft is journaled. The lower end of this lever 45 is bifurcated and carries pins 48 cooperating in a well known manner with a grooved collar 49 on the rear end of a stock feeding sleeve 50 enclosing the stock and reciprocable longitudinally in the spindle 6 and having usual resilient stock feeding and gripping fingers 51 on the front end of an interchangeable tip 50a threaded into the sleeve 50. The cam 36 also has a similar follower operated lever 52 pivoted at 53 below the frame extension 47, and similarly bifurcated at its lower end and connected to a collar 54 reciprocable on the rear end of the spindle 6. A cam and bell-crank mechanism 55 of usual construction save for the cut-away pins 55a shown in Fig. 13, operates on the rear end of a collet tube or sleeve 56 disposed between the stock feeding sleeve 50 and the spindle 6. As shown, cooperating resilient collet jaws 57, which grip the work in a usual manner, adjacent the tools 9 and 10, are formed on a short interchangeable collet member 58 recessed to receive the front extremity of the fingers 51 and disposed within the tapered front extremity of the collet sleeve 56. Further, a collar 59 is threaded on the front end of the spindle 6 and has a flange 60 projecting inward in front of a shoulder 61 on the collet jaws 57. As a result of this construction, when the bell cranks of the mechanism 55 are swinging to push the collet sleeve 56 forward, the stock is gripped by the jaws 57, while any slight variations in the diameter of the stock are taken care of by the resiliency of the pins 55a due to the cut away portions therein.

Cooperating with the stock as the same is fed forward by the cam 35, is also an improved stock stop mechanism, generally indicated at 62. Herein, this mechanism includes a socket sleeve 63 having an axial recess 64 in which the end of the stock is received, and this socket sleeve 63 carries the inner race of a ball bearing 65, while the outer race thereof is seated in a threaded extension 66 and held in place by a threaded sleeve 67. As shown, the stock stop mechanism 62 is interchangeably mounted, as by a pin 68, on a generally Y-shaped bracket 69 having its lower or vertical portion suitably fixed to a stud 70 parallel to and beneath the spindle and projecting in front of the latter, and also having its upper branching arms suitably fixed to similar forwardly projecting studs 71, 72 disposed in parallel relation to the spindle and laterally spaced from one another above the spindle 6 and below the cam shaft 1; these studs 71 and 72 also providing journals between the bracket 69 and the adjacent frame portion 1a for the cutting tool operating mechanism actuated by the roughing and finishing cams 37 and 38.

Referring to these cams 37 and 38, and, more particularly, to Figures 14 and 15, note that the cam 37 is disposed in rear of the cam 38, and that the latter is located on the front end of the cam shaft 1, while both cams are suitably adjustably fixed, as by set screws, to the shaft 1. Herein, the roughing cam 37 has an elongated working face 73 having abruptly curved portions 74 and 75 leading thereto and therefrom on opposite sides of a dwell portion 76. Attention here is also directed to the fact that the working face 73 between 74 and 75 is of generally spiral form and gradually approaches 76

a short cylindrical portion 73a, in such manner that when the roughing tool 9 is operated thereby, as hereinafter described, a heavy or so-called "hogging" cut is initially taken, and this cut gradually is reduced until the cylindrical portion 73a is reached, when no appreciable advance of the tool 9 occurs, while the work is trued into round form. The cam 38 has a working face 77 substantially shorter than the working face 73 and also has like abrupt working faces 78 and 79 leading thereto and therefrom at opposite ends of a substantially longer dwell portion 80. Here also the face 77 is spirally disposed and terminates in a cylindrical portion 77a similar to the portion 73a and having a like function. Thus, it will be apparent that, due to the like general conformation of both cams, each will actuate the tools 9 and 10 in such manner as gradually to reduce the cut on each tool until the portions 73a, 77a are reached, whereupon a minimum or finishing cut is obtained. In connection with these cams, it will be understood that the arrangement of the cams 37 and 38 may be reversed if desired, with, of course, a corresponding reversal of the tools 9 and 10.

Operatively associated with the cams 37 and 38 is also improved tool carrying and operating mechanism for the cutting tools 9 and 10. As shown, the roughing tool 9 is carried on a pivoted tool carrier 81 pivoted on the stud 71 between the frame portion 1a and the bracket 69, while the finishing tool 10 is carried on a similar carrier 82 pivoted in a similar position on the stud 72. Herein the two carriers 81 and 82 are biased to the non-cutting position of their tools by a coiled spring 83 connecting the same above the carrier pivots, while the carrier 81 has a cam follower 84 maintained in engagement with the roughing cam 37 by this spring, and the carrier 82 has a similar cam follower 85 similarly maintained in engagement with the finishing cam 38. As shown, the tools 9 and 10 are fixed to depending tool holders 81a, 82a adjustably mounted on the carriers 81 and 82 as hereinafter described and spaced below the pivots of the latter. Herein, the tool 9 is of a type adapted simultaneously to form portions of successive bullets, while the tool 10 is of a type adapted to cut off a leading bullet while finishing the rear extremity thereof, and while finishing the front end of the next following bullet.

Here it will also be noted that improved adjusting means is provided for each of the tools 9 and 10. The tools, as illustrated, are adjustable in suitable dovetails 86 in the tool holders 81a, 82a and the latter are suitably attached as by bolt and larger hole connections 88 to the lower ends of the carriers, while transverse bolts 89 serve to clamp and release the tools in the dovetails on these holders. As shown, the holder 81a is substantially longer than the holder 82a and carries the tool 9 on its lower end below a notch 81b so that the top of the tool 9 is substantially opposite the bottom of the tool 10. Further, the holders are received in transverse slots formed between transverse flanges 90 on the lower ends of the carriers 81, 82, and are adjustable in these slots by screws 91 carried on the flanges 90 and also by screws 92 carried by depending lugs 93 on the carriers 81, 82 opposite the outer ends of the slots. As shown, depending lugs 94 carrying adjustable screws 95 are also carried on the hubs of carriers 81, 82 and adapted

to engage flats 96 on members 97 carried on the frame portion 1a, and thereby limit the possible inward swinging movement of the carriers and the tools 9 and 10 carried thereby. Lubricant is also supplied to the tools by suitable pipe connections 98.

It will also be understood that the tools used are not necessarily limited to the particular construction illustrated, the particular construction of the same depending upon the work to be performed thereby. For example, in Figure 6, a modified form of tool is illustrated which is particularly adapted to use in connection with bullets of larger caliber and having a multiple transversely grooved rear end, as distinguished from the tapered end shown in Figure 4. In Figure 6, the tool 9a, corresponding to the tool 9, has its front end shaped and grooved as shown at 99 in such manner as to form a grooved flange on the rear end of the blank, while a separate forming tool 100 fixed to the holder in front of the tool 9a is also provided to form a further groove in front of that formed by the tool 9a. In this construction, the tool 10a, corresponding to the tool 10 is essentially similar to the latter save that in this construction the cutting off portion 101 extends slightly beyond the axis of the spindle and is of increased cross section in such manner as to enable it to cut off the substantially greater amount of metal left by the roughing tool 9a.

In order to enable the machine tool to operate at high speeds, improved bearings are also provided for the spindle 6. These, as shown, include an improved rear bearing, generally indicated at 102, and an improved front bearing, generally indicated at 103. Both of these are of the same general ball bearing type adapted to permit the spindle 6 to rotate freely at high speed. As shown, the bearing 102 includes like oppositely disposed outer rings or plates 104 suitably fixed to the rear frame upright 1a and enclosing a ball bearing including an outer race 105 and also an inner race 106. As shown, the outer race 105 is fixed against rotation in the frame and the inner race 106 is held in place on the spindle 6 by a threaded holding ring and washer 107 acting to position the inner race relative to a cooperating holding ring 108 abutting a thrust receiving shoulder 108a on the spindle 6 which is inwardly spaced from the adjacent ring 104. The front bearing 103 includes generally similar outer rings or plates 109 fixed to the front frame upright 1a, but instead of having a single ball bearing, in this bearing 103 a double ball bearing is provided including a plurality of adjacent outer races 110 fixed against rotation in the frame and a plurality of inner races 111 suitably positioned on the spindle by a holding ring 112 similar to the ring 107 and acting to maintain the front race in operative relation to a thrust shoulder 113 on the spindle 6 and corresponding to the shoulder 108a. Here also a sealing ring 114 is provided between the front plate 109 and the spindle 6.

As a result of these improved bearings and my improved driving mechanism, the speed at which the spindle may be operated without heating may be very high, the same when working on relatively soft steel, running as high as 2200 R. P. M. Hence, it is made possible to impart a substantially continuous rotation to the cam shaft 7 without appreciable variations in speed due to the intermittent action of the overrunning clutches 15. In fact, the drive is such that the intermittent impulses developed by the eccentric mechanisms

12 are so completely ironed out as not to be detectable in the operation of the mechanism at any normally high speed of operation thereof, since at even moderate speeds of the cam shaft, the roller clutch will overrun in such manner that only the more rapid part of each impulse of the eccentric 13 will be imparted to the shaft 7.

To speed up further the operation of the mechanism, improved speeding up mechanism is also provided to speed up the operation of the cam shaft 7 during the feeding movement of the stock. Reference is here first made to Figure 10, where it will be noted that the cam 37 has a portion 76a, which overlaps a portion 80a of the cam 38. Since, during the overlap of these two portions 76a and 80a, indicated in the right-hand bracket B in Figure 10, the tools 9 and 10 are stationary or being rapidly advanced into or retracted from cutting position, it is possible to speed up the feeding of the stock during the time interval represented by this bracket. Herein, this is done by providing a crank disc 115 fixed to the rear end of the cam shaft 7 and rotatable therewith and carrying a crank pin 116 which is connected to a rod 117, the upper end of which passes through a hole 118 in a stud 119 carried on the upper end of an upstanding bracket 120 on the frame extension 47. Herein also a coiled compression spring 121 is disposed between an adjustable abutment 122 carried by the rod 117 and a fixed abutment provided by the extremity of the stud 119.

As a result of this construction, when the parts assume the position shown in Figure 7 and the crank disc is rotated clockwise as shown therein, the crank pin 116 moves upward toward the position shown in Figure 8 and the coiled spring 121 is compressed until the dead center position shown in Figure 8 is reached. However, as the pin 116 moves further to the right and off dead center, due to the provision of the overrunning clutch mechanism 15, it is possible for the spring, when released from compression, to impart to the pin 116, and therefore to the cam shaft 7, a quick forward rotation during the operation of the stock feeding and gripping mechanisms which occurs in the time interval indicated by the bracket B. In practice, this amounts to such a substantial speeding up of the operation of the stock feeding and gripping mechanisms as to make these mechanisms operate substantially instantly, and thereby, in effect, reduce by substantially 23% the time required for a complete cycle of operation of the machine; the tools 9 and 10 thus, in effect, operating continuously, since they begin a new cutting operation substantially simultaneously with the termination of the last preceding cutting off operation.

Improved mechanism is also provided herein whereby it is made possible to disable the power drive and move the mechanism driven by the spindle through a complete cycle of operation manually at a slower speed and as a preliminary to the use of the power drive, in such manner as to be sure that the tool and other adjustments are correct. Herein, this mechanism is hand operated and includes a disabling mechanism operated by a hand lever 123 and a hand rotating mechanism operated by a hand crank 124 and connectible to a squared end 125 on the cam shaft 7. The disabling mechanism includes a shaft 126 journaled in the frame portions 1a above the shaft 7 and carrying between the portions 1a a plurality of spaced cam members 127 cooperating with upstanding ears 128 and 129 on the side plates 29 of the follower arms 14 of the overrun-

ning clutch mechanisms 15. Thus, whenever the lever 123 is rotated counter-clockwise, the cams 127, shown in their normal or inoperative position in Figure 12, engage the ears 128, 129 in such manner as thereby to swing the follower arms 14 to the right and consequently disengage the followers 33 from the outer eccentric rings 13 and thereby disconnect the power drive to the cam shaft 7. Consequently, by then connecting the crank 124 to the latter shaft and rotating this crank, the entire mechanism may be caused to go through a complete cycle of operation at slow speed in such manner that a preliminary check of the timing and operation of all of the mechanisms is made possible, during which any necessary adjustments may be made before the connection of the power.

As a result of my improvements, it is made possible to produce a complete bullet turning machine of such compact construction as to make it possible for fifty or one hundred such machines to be disposed in a single bank and thereby markedly facilitate the supply of stock thereto and the handling of the cuttings and the finished product, while materially reducing labor costs for a given production. In Figure 1, I have illustrated the support 2 as including a top bench portion 130 and having supporting legs 131 and a conveyor, generally indicated at 132, extending along in front of the support and beneath the cutting tools. As shown, the conveyor belt 133 is driven by a pulley 134 rotated by a belt 135 and carried on a shaft 136 journaled in the legs 131 while the upper reach of the conveyor moves in a trough 137 and the lower reach runs under a top shield 138. Note also that a chamber 139 is provided between the shield 138 and a top support 140 on which the upper conveyor reach 133 moves. In Figure 20, an installation comprising a plurality of adjacent machines is illustrated associated with a common conveyor. Thus, the cuttings, lubricant, and finished bullets fall onto the upper reach 133 of the conveyor, so that the cuttings and bullets are carried away by the conveyor 133 and any lubricant passes into the chamber 139, from which it is suitably delivered for cleaning and returned to use.

In the operation of the complete machine, it will be apparent that after the mechanism has been preliminarily operated and adjusted as heretofore described, the stock will be fed and gripped and operated upon by the tools 9 and 10, in such manner as successively to form and cut off bullets while partially forming the next following bullets, all as heretofore described in connection with the operation of the component mechanisms, and while markedly increasing the production obtainable from a given investment in equipment and available floor space. Here attention is directed particularly to the fact that, irrespective of the use of an intermittent drive for the tool feed, the long cutting faces on the tools, or the heavy cuts initially taken thereby, it is made possible to produce accurately round work due to the provision of the cylindrical portions in the tool feeding cams which act to hold the tools against the work without advancing the tools and in such manner as thereby to insure accurate truing of the work into round form.

In Figures 16 to 18, I have shown a modified form of eccentric mechanism. In this construction, instead of two separate eccentric mechanisms, each of the double ring type and spaced on opposite sides of the flywheel as heretofore, both of the eccentric mechanisms are of the single

ring type and carried on the hub of the flywheel. As shown, each eccentric includes an eccentric ring 141 pivoted at one side at 142 to the pulley hub 143 and having improved adjustable connections 144, opposite the pivot 142, for clamping the ring in different positions of eccentric adjustment about its pivot. Herein, the ring 141 adjacent the connections 144 is provided with a series of radially located indentations 145, nine being illustrated. Cooperating with these indentations is a toothed washer 146, herein having three teeth 147, selectively receivable in the indentations 145 in different angular positions of the ring 141 relative to its pivot. This washer 146 is clamped in place by a cap screw 148 having a shank extending through the washer and through an elongated slot 149 in the eccentric ring 141 and threaded in the hub 143. Thus, at the same time that the structure is simplified and reduced in cost, the eccentric action of the rings 141 may be varied with facility, certainty and uniformity and while the adjusting mechanism is readily accessible and visible, by merely releasing the screw 148, swinging the ring 141 about its pivot 142, and then again tightening the screw.

In Figure 19, I have shown a modified form of the overrunning clutch shown in Fig. 12. This construction is essentially similar to that shown therein, save that the number of spring biased 30 rollers has been materially increased, eight being shown. In this construction, it will also be noted that, due to the larger number of the same, the angle at which they act has been somewhat increased.

In Figures 21 to 23, a modified form of the speeding up mechanism for the cam shaft 7, has also been shown. In this construction, a rear cam 127a, similar to the manually operated cams 127, is carried on the rear end of shaft 126. However, this cam 127a is carried on a hub 150 which is freely rotatable on shaft 126. This hub 150 also has on the opposite side thereof a laterally and rearwardly extending arm 151 extending through an arcuate slot 151a in the adjacent frame portion 1a and carrying a follower 152 on its extremity. This follower 152, in turn, engages both the periphery 153 of the end wall of the cam 36 and a notched operating portion 154. Thus, while the cam 36 rotates clockwise and the follower 152 rides on the periphery 153 thereof, the rear cam 127a will be maintained in engagement with its ear 129. When, however, the follower 152 drops into the notched portion 154, the rear ear 129 will be released in such manner as thereby to reconnect the power drive while the follower 152 remains in the notched portion 154, and thereby speed up the rotation of the cam shaft 7 during the stock feeding and gripping operations. Thus, the rear cam mechanism will be operated intermittently to speed up the shaft 7, while the latter will be driven through only the front drive.

It will be understood that I also contemplate the use, when desired, of other usual forms of 65 ratchet mechanism in lieu of the particular overrunning clutches illustrated. Under certain conditions, I also contemplate the use of any suitable or usual form of spring, if desirable, in connection with the collet mechanism in order to insure release of the jaws. Further, it will be understood that I contemplate the use of any suitable or usual form of cams on the cam shaft for operating the stock gripping and feeding mechanisms in the manner set forth. It will also 70 be understood that, in connection with the speed

up mechanism, I may use, if desired, a larger or heavier crank disc than that illustrated in order to obtain greater benefit from inertia, as, for example, utilizing a peripheral flywheel effect.

While I have in this application specifically described certain embodiments which my invention may assume in practice, it will be understood that these are shown for purposes of illustration, and that the invention may be modified and embodied in various other forms without departing from its spirit or the scope of the appended claims.

What I claim as new and desire to secure by Letters Patent is:

1. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, and driving means including cooperating operatively connected driving mechanisms between said spindle and shaft for generating intermittent rotative impulses for said cam shaft at sufficient speed to transform said impulses into substantially continuous rotation of said shaft.

2. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, cooperating operatively connected driving mechanisms between said spindle and shaft for generating intermittent rotative impulses for said cam shaft, including cam means on said spindle and cam shaft actuating means successively operated thereby to rotate said cam shaft, and means for rotating said spindle at sufficient speed to transform said impulses into substantially continuous rotation of said shaft.

3. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle, and means for rotating said cam shaft intermittently operated by said eccentric mechanism.

4. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle, and overrunning clutch mechanism operated by said eccentric mechanism to rotate said cam shaft.

5. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle and comprising a plurality of angularly related eccentrics, and a plurality of means for rotating said cam shaft and each intermittently operated by a different eccentric to rotate said cam shaft.

6. In a machine tool, a power driven work rotating spindle, stock feeding and gripping mechanisms, a cam shaft controlling said mechanisms, stock forming and cutting off tool means operated by said cam shaft in timed relation to said feed-

ing and gripping mechanisms, eccentric mechanism rotatable by said spindle having a plurality of angularly related eccentrics, and means for rotating said cam shaft including a plurality of overrunning clutch mechanisms each operated by a different eccentric to rotate said cam shaft.

7. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle having a plurality of angularly related eccentrics, and means for rotating said cam shaft including a plurality of overrunning clutch mechanisms each operated by a different eccentric to rotate said cam shaft, said eccentrics being oppositely located and said overrunning clutches having operating arms alternately operated by said eccentrics.

8. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle having a plurality of angularly related eccentrics, means including a plurality of overrunning clutch mechanisms each operated by a different eccentric for rotating said cam shaft, said eccentrics being oppositely located and said overrunning clutches having operating arms alternately operated by said eccentrics, and means for enabling adjustment of the eccentricity of said eccentrics to vary the cam shaft speed while maintaining them oppositely disposed.

9. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle having a plurality of angularly related eccentrics, means including a plurality of overrunning clutch mechanisms each operated by a different eccentric for rotating said cam shaft, said eccentrics being oppositely located and said overrunning clutches having operating arms alternately operated by said eccentrics, and means for enabling adjustment of the eccentricity of said eccentrics to vary the cam shaft speed while maintaining them oppositely disposed, including inner adjustable eccentrics on said spindle and carrying said first mentioned eccentrics.

10. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, eccentric mechanism rotatable by said spindle having a plurality of angularly related eccentrics, means including a plurality of overrunning clutch mechanisms each operated by a different eccentric for rotating said cam shaft, said eccentrics being oppositely located and said overrunning clutches having operating arms alternately operated by said eccentrics, and means for enabling adjustment of the eccentricity of said eccentrics to vary the cam shaft speed while maintaining them oppositely disposed, including pivots for said eccentrics rotatable with said spindle and means for position-

ing said eccentrics into different positions about their pivots to vary the eccentricity thereof.

11. In a machine tool, work rotating mechanism, a tool for operating on the rotating work therein having an elongated cutting edge bearing on the work and simultaneously forming the rear end of one work piece and the front end of the next, tool feeding mechanism including means for feeding the tool first rapidly into the work and thereafter with a gradually reducing depth of cut and cooperating means operative upon the completion of the feeding operation of said first mentioned means for holding the tool without substantial advancement toward the work, to produce round work, and means for intermittently operating said feeding mechanism to break the chip formed by the tool.

12. In a machine tool, work rotating mechanism, a tool for operating on the rotating work therein, intermittently operated feed operating means, and tool feeding mechanisms including a tool feeding cam intermittently operated by said operating means and having an operating portion for advancing the tool to the work and also having a substantially cylindrical portion operative upon the tool upon the completion of the tool advancing movement for holding the tool against the work without substantial advancement of the tool, to produce round work.

13. In a machine tool, work rotating mechanism, a tool for operating on the rotating work therein, feed operating means rotatable at predetermined variable feeding rates through successive predetermined cycles, and tool feeding mechanism including a tool feeding cam rotatable by said feed operating means at said variable rates through said successive cycles and having an operating portion for advancing the tool to the work and also having a substantially cylindrical portion operative upon the tool upon the completion of the tool advancing movement for holding the tool against the work without substantial advancement of the tool, to produce round work.

14. In a machine tool, work rotating mechanism, roughing and finishing tools for operating on the rotating work therein, each having an elongated cutting edge bearing on the work and simultaneously forming the rear end of one work piece and the front end of the next, and tool feeding mechanism including intermittently operated feed operating means rotatable at predetermined variable feeding rates through successive predetermined cycles, and a separate tool feeding cam for each of said tools intermittently operated by said operating means and rotatable at said variable rates through said successive cycles, each of said cams having an operating portion for advancing the tool to the work and each also having a substantially cylindrical portion operative upon the completion of the tool advancing movement for holding the tool against the work without substantial advancement of the tool, to produce round work.

15. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, cooperating operatively connected driving mechanisms on said shafts for rotating said cam shaft including an overrunning clutch, and means for speeding up the rotation of said cam shaft relative to the

drive through said clutch during a portion of the cycle of operation of said feeding and gripping mechanisms.

16. In a machine tool, a power driven work rotating spindle, stock feeding and gripping mechanisms, a cam shaft controlling said mechanisms, stock forming and cutting off tool means operated by said cam shaft in timed relation to said gripping and feeding mechanisms, cooperating operatively connected driving mechanisms on said shafts for rotating said cam shaft including an overrunning clutch, and means for speeding up the rotation of said cam shaft relative to the drive through said clutch between the end of one cutting operation of said tool means and the beginning of the next cutting operation thereof.

17. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, cooperating operatively connected driving mechanisms on said shafts for rotating said cam shaft including an overrunning clutch, and means for speeding up the rotation of said cam shaft relative to the drive through said clutch including rotatable means carried by said cam shaft and means cooperating with and controlled by said rotatable means for imparting an additional forward rotative impulse to said cam shaft.

18. In a machine tool, a power driven work rotating spindle, stock feeding and gripping mechanisms, a cam shaft controlling said mechanisms, stock forming and cutting off tool means operated by said cam shaft in timed relation to said gripping and feeding mechanisms, cooperating operatively connected driving mechanisms on said shafts for rotating said cam shaft including an overrunning clutch, and means for speeding up the rotation of said cam shaft relative to the drive through said clutch between the end of one cutting operation of said tool means and the beginning of the next cutting operation thereof, including a crank rotatable with said cam shaft and spring connected means for speeding up the rotation of said crank when the same passes dead center with the spring stressed.

19. In a machine tool, a power driven work rotating spindle, stock feeding and gripping mechanisms, a cam shaft controlling said mechanisms, stock forming and cutting off tool means operated by said cam shaft in timed relation to said gripping and feeding mechanisms, cooperating operatively connected driving mechanisms on said shafts for rotating said cam shaft including an overrunning clutch, and means for speeding up the rotation of said cam shaft relative to the drive through said clutch between the end of one cutting operation of said tool means and the beginning of the next cutting operation thereof, including a notched cam rotatable with said cam shaft and means including a follower movable into the notch therein for imparting an additional forward rotative impulse to said cam shaft.

20. In a machine tool, a power driven work rotating spindle, stock feeding and gripping mechanisms, a cam shaft controlling said mechanisms, stock forming and cutting off tool means operated by said cam shaft in timed relation to said gripping and feeding mechanisms, eccentric mechanism rotatable by said spindle, overrunning clutch mechanism operated by said eccentric mechanism and rotating said cam shaft, and

mechanism for manually rotating said cam shaft to operate said feeding and gripping mechanisms and said tool means while the spindle rotates, including means for temporarily disabling said overrunning clutch mechanism and means for manually rotating said cam shaft while the same are disabled.

21. In a machine tool, a frame, a power driven work rotating spindle thereon, stock feeding and gripping mechanisms thereon, a cam shaft on said frame controlling said mechanisms, a plurality of pivoted tool carriers having pivot members on said frame between said cam shaft and spindle and also having spring means biasing said carriers toward the non-cutting position of said carriers, roughing and finishing tools carried on said carriers below said pivot members, cooperating means on said cam shaft and cam followers on said carriers for feeding said tools to the work, a depending stock stop bracket carried on said pivot members in front of said carriers and fixed to said frame below said spindle, and a freely rotatable stock stopping and receiving member journaled in said bracket and coaxial with the work in said spindle.

22. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, and means for driving said cam shaft intermittently from said spindle.

23. In a machine tool, a power driven work rotating spindle, stock feeding and gripping mechanisms, a cam shaft controlling said mechanisms, stock forming and cutting off tool means operated by said cam shaft in timed relation to said feeding and gripping mechanisms, and means for intermittently rotating said cam shaft.

24. In a machine tool, a power driven work rotating spindle, a cam shaft driven from said spindle, stock forming and cutting off tool means operated by said shaft, an eccentric on said spindle, and overrunning clutch mechanism on said cam shaft having a swinging follower carried by said cam shaft and oscillated by said eccentric to actuate said clutch mechanism and rotate the shaft.

25. In a machine tool, a power driven work rotating spindle, a cam shaft driven from said spindle, stock forming and cutting off tool means operated by said shaft, a plurality of oppositely disposed eccentrics on said spindle, and a plurality of overrunning clutch mechanisms on said shaft, each of said clutch mechanisms having a swinging follower carried by the shaft and oscillated by one of said eccentrics to actuate its clutch mechanism and rotate the shaft.

26. In a machine tool, a power driven work rotating spindle, stock feeding and gripping mechanism, a cam shaft controlling said mechanism, stock forming and cutting off tool means operated by said cam shaft in timed relation to said feeding and gripping mechanisms, cooperating operatively connected driving mechanism

on said spindle and shaft for rotating the latter from the former, and means for speeding up the rotation of said shaft relatively to that effected by said driving mechanism.

5 27. In a machine tool, a power driven work rotating spindle, stock feeding and gripping mechanism, a cam shaft controlling said mechanism, stock forming and cutting off tool means operated by said cam shaft in timed relation to said feeding and gripping mechanisms, cooperating operatively connected driving mechanism on said spindle and shaft for intermittently rotating the latter, and means for speeding up the rotation of said shaft relatively to that effected by said mechanism.

10 28. In a machine tool, a power driven work rotating spindle, stock feeding and gripping mechanism, a cam shaft controlling said mechanism, stock forming and cutting off tool means operated by said cam shaft in timed relation to said feeding and gripping mechanisms, cooperating operatively connected driving mechanism on said spindle and shaft for intermittently rotating the latter, and means for speeding up the rotation of said shaft relatively to that effected by said mechanism, said speeding up means comprising an eccentric on said shaft, a spring connected to said eccentric, and said spring being compressed by the rotation of said shaft.

15 29. In a machine tool, a power driven work rotating spindle, stock feeding and gripping mechanism, a cam shaft controlling said mechanism, stock forming and cutting off tool means operated by said cam shaft in timed relation to said feeding and gripping mechanisms, cooperating operatively connected driving mechanism on said spindle and shaft for intermittently rotating the latter, and means for speeding up the rotation of said shaft relatively to that effected by said mechanism, said speeding up means comprising an eccentric on said shaft, a spring connected to said eccentric, and said spring being compressed by the rotation of said shaft, said spring being compressed during one phase of the rotation of said shaft and expanding to impart a rotating impetus to the shaft during another phase of its rotation.

30 30. In a machine tool, a power driven work rotating spindle, stock feeding and gripping mechanism, a cam shaft controlling said mechanism, stock forming and cutting off tool means operated by said cam shaft in timed relation to said feeding and gripping mechanisms, cooperating operatively connected driving mechanism on said spindle and shaft for intermittently rotating the latter, and means for speeding up the rotation of said shaft relatively to that effected by said mechanism, said driving mechanism comprising a plurality of overrunning clutches on said shaft, and said speeding up means comprising a controlling member for one of said clutches and cam means on the shaft for actuating said controlling member.
